UNITED STATES PATENT OFFICE.

MAX PETZOLD, OF ZITTAU, GERMANY.

PROCESS OF TREATING TEXTILE FABRICS.

1,058,459.

Specification of Letters Patent.

Patented Apr. 8, 1913.

Application filed September 6, 1911. Serial No. 647,977.

To all whom it may concern:

Be it known that I, MAX PETZOLD, a subject of the German Emperor, and residing at Zittau, in Saxony, Germany, have invented 5 a certain new and useful Improved Process of Treating Textile Fabrics, of which the following is a specification.

My invention relates to a process for treating the textile fabrics steeped in soda- 10 lye for the purpose of mercerization and almost completely delivered from lye by means of steam.

If the cotton fibers of the fabrics have left the parchment like state into which they 15 had come by being soaked with soda lye, the same enter a flabby or flaccid state for a short time during which they are easily stretched in width. I have observed that this quickly passing flabby or flaccid state 20 of the cotton fibers or the fabric which occurs after almost completely delivering the fabrics from soda lye by means of steam may be prolonged by the influence of the heat of the liquid for instance by the heat of a hot 25 bath of water or weak lye.

My invention consists in stretching the fabric by means of clamps during the thus effected prolongation of the above described state far beyond its original width. This 30 far extended stretching of the fabric effects a much higher gloss without shrinkage of the fabric taking place when the stretching is released.

According to the present invention the 35 fabric is led through a hot bath of water or weak lye after being almost completely delivered from the soda lye by means of steam. The effect of the bath is due to the temperature of the liquid forming the bath and 40 not in the strength of the soda-lye used, the same being immaterial for the intended effect.

The new process may be explained with 45 regard to an apparatus for carrying the invention into effect which is diagrammatically shown in the accompanying drawings, wherein:

Figure 1 is a longitudinal section through the same, whereas Fig. 2 is a top plan view 50 of the middle part of the apparatus.

Referring to the drawing, the apparatus 55 comprises the casing 1 having end walls 2 and 6 extending into the trough 4 and the vat 5, respectively, provided at the ends of the casing. In front of the trough 4 is the roller 7 carrying the fabric to be treated,

the guide roll 8 and the width-stretching roll 9. Within the trough 4 below the wall 2 is a width-stretching roll 10. In the casing 1 are arranged in known manner the 60 pairs of press rolls 11, 12 and 13, 14, and in front of each of these pairs are two width-stretching rolls 15, 16, and 17, 18. Between the rolls 15 and 16 are steam-spraying pipes 19, 20, and between the roll 16 and the pair 65 of press rolls 11, 12, the steam-spraying pipes 21, 22. Further, between the rolls 17, 18 are the steam-spraying pipes 23, 24, and between the roll 18 and the pair of pressing rollers 13, 14 the steam-spraying pipes 25, 70 26. Behind the pair of rolls 13, 14 are three guide rolls 27 for guiding the fabric at the outlet end of the casing.

Now between the vat 5 and the rinsing vat 28 I provide the bath 29 which may be 75 hot water or weak lye. The front guide rolls 30, 31, 32, 33 are for conducting the fabric into the bath and toward the rear guide rollers 34, 35 and 36 and the pair of press rolls 37 and 38. At both sides of the 80 fabric in the bath I provide stretching chains 39 which while traveling from the front toward the rear through the bath 29 gradually move apart.

The vat 28 is divided into two compartments 40 and 41, of which the compartment 40 may contain acid and compartment 41 water. The top of the compartment 41 is provided with a cover 60.

Now when the fabric leaves the casing 1, 90 it still contains a very little lye. In the bath 29 the fabric is seized by the two stretching chains and gradually stretched to the width it originally possessed before being mercerized. This stretching of the fabric in width in the hot bath has the advantage that the fabric does not shrink again because it is immediately led into the compartment 40 containing acid. A further advantage is that the fabric receives a better 100 gloss, this being particularly attained by the stretching in width after the removal of the lye.

The guide rolls 42, 43, 44, 45 and 46 are provided for conducting the fabric to the 105 pair of squeezing rolls 47, 48. In the compartment 41 are guide rolls 49, 50, 51 by which the fabric is led toward the pair of squeezing rolls 52, 53. For heating the water in the compartment 41 a steam coil 54 110 is provided.

55 designates a tank containing weak lye

and connected by pipes 56 and 56' with the spraying pipes 57 and 57', respectively, for spraying the fabric with weak lye. The lye running off the fabric collects in the trough 4, overflows onto the bottom 58 whence it can be passed into vat 5 as required.

It will be readily understood that the width-stretching rolls may be replaced by ordinary guide rolls without departing from the scope of the invention.

I claim:—

The herein-described process of treating

textile fabrics which consists in steeping the fabric in soda lye for the purpose of mercerization in steaming the fabric to practically fully eliminate the lye, in passing the fabric through a hot aqueous bath, and in stretching the fabric laterally of its length while in such bath.

In testimony whereof, I affix my signature in the presence of two witnesses.

MAX PETZOLD.
